UNITED STATES PATENT OFFICE.

HAROLD R. HAERR, OF CINCINNATI, OHIO, ASSIGNEE TO THE GRUEN WATCH COMPANY, OF CINCINNATI, OHIO, A CORPORATION OF OHIO.

DESIGN FOR A DISPLAY CASE.

Application filed May 20, 1922. Serial No. 2,336. Term of patent 14 years.

To all whom it may concern:

Be it known that I, HAROLD R. HAERR, a citizen of the United States of America, and a resident of Cincinnati, in the county of Hamilton and State of Ohio, have invented a new, original, and ornamental Design for a Display Case, of which the following is a specification, reference being had to the accompanying drawing, forming part thereof.

Fig. 1 is a perspective view showing the top, front and one side of a case, showing my new design.

Fig. 2 is an end elevation of a case showing my new design.

I claim:

The ornamental design for a display case, as shown.

HAROLD R. HAERR.
